UNITED STATES PATENT OFFICE.

ADELBERT AMES, JR., OF TEWKSBURY, MASSACHUSETTS.

REFLECTOR.

1,216,912.

Specification of Letters Patent. Patented Feb. 20, 1917.

Application filed September 30, 1916. Serial No. 122,969.

To all whom it may concern:

Be it known that I, ADELBERT AMES, Jr., a citizen of the United States, and resident of Tewksbury, in the county of Middlesex 5 and State of Massachusetts, have invented new and useful Improvements in Reflectors, of which the following is a specification.

This invention relates to reflecting apparatus comprising a concave reflecting member and means for detachably securing it to an incandescent lamp bulb or other source of light. The apparatus may be employed alone as a show window reflector, desk light reflector, etc., but it is particularly designed 10 to be employed in combination with a paraboloidal or other type of light projector as a deflector for deflecting light to the main reflecting surface in such manner that it will be projected wholly on one side of a plane 15 containing the axis of the projector.

Apparatus of the same general character as the subject matter of this application is disclosed in my copending application Sr. No. 102,086, filed June 6, 1916, of which this 20 is a continuation in part. In the former application I have set forth at length the underlying principles and the theory of operation of apparatus of this general character, which, in the form illustrated, is adapted to 25 project a concentrated beam of light in and below a horizontal direction without producing upward glare; and reference may be had to the former application for the principles and optical consideration pertaining 30 to the apparatus.

One object of this invention is to provide means for mounting the reflector on the ferrule of the lamp in such manner that the weight of the reflector is carried by the ferrule and not by the lamp bulb, thereby 35 eliminating the tendency to loosen the bulb from the ferrule due to the weight of the reflector, which tendency has been common in apparatus having the reflector supported by 40 the bulb, especially where such apparatus has been employed on vehicles subjected to severe vibration.

A further object of the invention is to provide means for mounting the reflector on the ferrule in a limited space, yet mounting the reflector rigidly and securely, whereby the lamp may be inserted into and secured 45 in a socket as in the absence of the reflector and mounting means. A still further object is to provide a reflector comprising two

parts which may be separated to permit the insertion of the lamp and to provide improved means for detachably securing the two parts together. A still further object of the invention is to provide means for mounting the reflector so that the elasticity of one or both parts of the reflector will tend to cause the mounting means to grip the support, which in the preferred form is the ferrule, and to provide elastic means to supplement the elastic action of the reflector when desired.

In the accompanying drawings,

Figure 1 is a vertical longitudinal section of one embodiment of my invention;

Fig. 2 is a side elevation of the deflector shown in Fig. 1; and

Fig. 3 is a front elevation of the deflector shown in Figs. 1 and 2.

In the illustrated embodiment of my invention, P comprises a paraboloidal reflector having a lamp socket 1 adjustably mounted in the reflector and adapted to receive the ferrule 2 of the incandescent lamp bulb 3. Within the lamp bulb is the incandescent filament 4 which may, for example, be V-shaped, having its apex in the focus of the reflector and having its legs symmetrically disposed with respect to the axis of the reflector, whereby the light radiating downwardly from the source strikes the reflector P in such manner as to be projected in and below a horizontal direction. The lamp bulb is secured in the lamp socket by means of bayonet catches 6 on the lamp ferrule which fit in slots 7 in the lamp socket in a well-known manner.

The deflector D has a substantially spherical contour and is preferably positioned with its center in the rear of the light source. The deflector D' is preferably also of spherical contour and has a shorter radius of curvature than the deflector D. The deflector D' has a depending apron 8 which is split at 9 and which has a circular opening 11 adapted to fit over the ferrule 2 of the lamp, recesses 12 being provided to permit the passage of the pins 6 on the ferrule. The sides of the deflector D' are flared outwardly as indicated in Fig. 3 at 13, the outward flare 105 being such that the lower edges of the deflector D' meet the lower edges of the deflector D. The general structure of the deflectors D and D' and their positions with respect to each other, the light source, and 110

the reflector P, is similar to that described in my copending application above referred to, and reference may be had to that application for a more detailed description of the 5 optical considerations involved.

The specific embodiment of the means for attaching the two deflectors together comprises flanges 14 on the interior of the deflector D coöperating with the lower edges 16 of the deflector D', together with shoulders 17 on apron 8 and ears 18 attached to the forward lower edges of the sides of deflector D' and projecting outwardly through recesses 19 in the lower edges of the opposite 15 sides of deflector D. The internal flanges 14 are preferably formed by slightly curling the rear lower edges of the deflector D inwardly, as indicated in Fig. 3, in order to form bearing surfaces for the lower edges 20 16 of the deflector D'. The shoulders 17 are preferably lateral extensions of the apron 8, these shoulders being preferably positioned at the rear of the flanges 14.

The ears 18 are preferably formed as an 25 integral part of the deflector D' and as a forward continuation of the forward lower edges of the deflector in the nature of narrow bands. These bands are bent outwardly at angles of 90°, respectively, into the vertical plane of the forward edge of the deflector D' and are then bent rearwardly at angles of 90°, respectively, at distances of about one-eighth of an inch from the deflector, thus forming radial portions 21 and 30 portions 22 which are substantially parallel with the axis of the lamp, the latter portions serving as operating surfaces for applying pressure to the ears to detach the deflectors from each other. The upper edge 23 of each 35 40 of the ears 18 is adapted to bear against the top of the recesses 19.

In attaching the deflectors to a lamp bulb the ferrule of the lamp bulb is inserted through the circular opening 11 in the apron 45 8 from the forward side, and owing to the elasticity of the deflector D' the apron is caused tightly to grip the ferrule and thereby maintain the deflector D' in adjusted position. The outer deflector D is then secured 50 in position by inserting the tip of the lamp bulb into the spring 26 and recess 27, forcing the deflector D backwardly against the action of the spring 26 and downwardly so that the recesses 19 fit over the ears 18 and 55 then by forcing the deflector D downwardly still farther, the flanges 14 spring over the lower edges 16 of the deflector D'. In this position the reflector D is rigidly held owing to the fact that the lower edges 16 of 60 the deflector D' are pressing downwardly on the flanges 14 and shoulders 17 and ears 18 are pressing upwardly on the deflector D in the rear of and in front of the flanges 14, respectively.

65 Additional means may be employed to

prevent rotation of the deflectors with respect to the lamp bulb but I have found that such means are not ordinarily necessary owing to the fact that the elasticity of both the deflectors tends to cause the two portions of the apron 8 tightly to grip the ferrule of the lamp, the deflector D' being so shaped as to force the two portions of the apron inwardly and the deflector D being so shaped as to increase this action when snapped over the deflector D'. 70 75

For the purpose of supplementing the elastic action of the deflectors, I may provide additional elastic means to urge the two portions of the apron 8 together and thereby to increase the grip of the apron upon the ferrule. This means may, for example, take the form of a U-shaped spring 28 the upper ends of which are hooked inwardly over flanges 29 struck-up from or brazed to the apron 8. The spring is so formed that it must be spread outwardly against the force of its own elasticity to be hooked over the flanges, whereby it urges the two portions of the apron together when placed in position. The spring 28 is spaced outwardly from the opening 11 such a distance that the spring does not interfere with the socket 1 when the lamp is mounted therein, and owing to the markedly short dimension, measured along the axis of the lamp, of the member for mounting the deflectors on the ferrule, the lamp can be mounted in a socket of the type illustrated or in a socket of any other ordinary type 100 without any interference from the mounting means. Moreover, the deflectors do not engage the lamp bulb, except through the medium of spring 26 which may or may not be employed, but on the contrary they are 105 mounted on the ferrule which is a substantial portion of the apparatus and is unaffected by the weight of the reflectors. 90 95

In removing the deflector D from the apparatus, inward pressure is simultaneously applied to the outer portions 22 of the ears 18 causing the lower portions of the deflector D' to spring inwardly and disengage the flanges 16, thereby permitting the deflector D to be moved upwardly and forwardly 110 115 away from the deflector D' and lamp bulb 3.

It is to be noted that the words above, below, upper, upward, lower, downward, etc., are used throughout the specification and claims merely for convenience in referring to relative locations and directions, and that my invention is not limited to apparatus employed solely in the position herein described. On the contrary, the invention is applicable wherever it is desired to reflect 125 light in a certain direction. 120

I claim:

1. In reflecting apparatus for a lamp having a ferrule adapted to fit in a socket, the combination of a shade, and a divided sup- 130

- porting member for the shade, the supporting member being arranged to receive the ferrule of the lamp between the two parts thereof.
5. 2. In reflecting apparatus for a lamp having a ferrule adapted to fit in a socket, the combination of a reflector, and means for supporting the reflector on the ferrule between the lamp and the socket, the supporting means being constructed and arranged so as yieldingly to grip the ferrule on opposite sides.
10. 3. In reflecting apparatus for a lamp having a ferrule adapted to fit in a socket, the combination of a reflector, and a divided member for supporting the reflector on the ferrule between the lamp and the socket, the divided member being constructed and arranged to receive the ferrule between the two parts thereof and to grip the ferrule between the two parts by virtue of its elasticity.
15. 4. In reflecting apparatus for a lamp, the combination of a reflector having elasticity, and a divided supporting member connected to the reflector, the reflector and supporting member being constructed and arranged to receive the ferrule between the two parts of the supporting member and to grip the ferrule between the two parts by virtue of the elasticity of the reflector.
20. 5. In reflecting apparatus for a lamp having a ferrule adapted to fit in a socket, the combination of a concave shade, and a supporting member therefor, the supporting member being constructed and arranged to be mounted on the ferrule of the lamp between the lamp and the socket and detachably to engage the shade.
25. 6. In reflecting apparatus for a lamp having a ferrule adapted to fit in a socket, the combination of a concave shade, and a supporting member therefor, the supporting member being constructed and arranged to be mounted on the ferrule of the lamp between the lamp and the socket and detachably to engage the edge of the shade, thereby to support the shade.
30. 7. Reflecting apparatus for a lamp having a ferrule adapted to fit in a socket comprising a reflector, a supporting member therefor fitting between the lamp bulb and the socket, and yielding means causing the supporting member to grip the ferrule.
35. 8. Reflecting apparatus for a lamp having a ferrule adapted to fit in a socket comprising a concave reflector, a thin supporting member therefor fitting between the lamp bulb and the socket, and a spring mounted on the supporting member, the spring at least partially surrounding the ferrule and causing the supporting member to grip the ferrule.
40. 9. Reflecting apparatus comprising a concave reflector, a support adapted detachably
- to engage the reflecting member on opposite sides along its edges, and means to maintain the reflector in position thereon.
10. Reflecting apparatus comprising a concave reflecting member, a supporting member therefor adapted to engage the edges of opposite sides of the reflecting member, and interlocking means on the members for maintaining the reflecting member in position on the supporting member.
15. Reflecting apparatus comprising a concave reflecting member, a supporting member, the two members having interfitting portions, one of the members having one or more recesses and the other member having one or more shoulders fitting into the recesses, whereby the two members may be detachably secured together.
20. Reflecting apparatus comprising a concave reflector, a support therefor adapted to engage the lower edges of opposite sides of the reflector, the reflector having recesses on opposite sides thereof, and shoulders on the support interfitting with the recesses to maintain the reflector in position on the support.
25. Reflecting apparatus comprising a reflector, flanges on opposite sides of the reflector, and a support arranged to engage the upper side of the flanges and to engage the lower side of other portions of the reflector, whereby the reflector may be maintained in position on the support.
30. Reflecting apparatus comprising a concave reflector, flanges on opposite sides of the interior of the reflector, a support arranged to engage the upper side of the flanges, shoulders on the support for engaging the lower side of the reflector on one side of the flanges, and ears on the support for engaging the lower side of the reflector on the other side of the flanges.
35. Reflecting apparatus comprising a concave reflector, flanges on opposite sides of the interior of the reflector, a support arranged to engage the upper side of the flanges, shoulders on the support for engaging the lower side of the reflector on one side of the flanges and ears on the support for engaging the lower side of the reflector on the other side of the flanges, the ears projecting outwardly so that the support may be released from engagement with the flanges by pressing inwardly upon the ears.
40. Reflecting apparatus comprising a concave reflector, flanges on opposite sides of the interior of the reflector, a support arranged to engage the upper side of the flanges, shoulders on the support for engaging the lower side of the reflector rearwardly of the flanges, and ears on the support projecting through recesses in the lower edges of the reflector in front of the flanges, whereby the reflector is accurately maintained in position on the support and whereby the re-

flector may be disengaged from the support by pressing upon said ears.

17. Reflecting apparatus comprising a concave reflector, portions of the lower edges of opposite sides of the reflector being curved inwardly to form flanges, and a support for the reflector, the support having means to engage the upper side of the flanges and having means to engage the lower side of portions of the reflector for holding the reflector in position.

18. Reflecting apparatus comprising a substantially spherical reflecting surface, a second substantially spherical reflecting surface at least in part within the first reflecting surface, the second reflecting surface having a smaller radius of curvature and being positioned at least in part rearwardly of the first reflecting surface, whereby the device may be positioned in the restricted space between a light source and the reflecting surface of a projector having a comparatively small focal length.

19. Reflecting apparatus comprising a substantially spherical reflecting surface, a second substantially spherical reflecting surface at least in part within the first reflecting surface, the second reflecting surface having a smaller radius of curvature and having its lower edges flared outwardly to meet the first reflecting surface, means on the first reflecting surface to engage said edges, and means for maintaining said means in engagement with said edges.

20. Reflecting apparatus comprising a concave reflector, a smaller concave reflector at least in part within the first reflector, the lower portions of the smaller reflector extending outwardly to meet the outer reflector, means on the outer reflector for engaging said portions, and means for maintaining said means in engagement with said portions.

21. Reflecting apparatus comprising a concave reflector, a smaller concave reflector at least in part within the first reflector, portions of the lower edges of the outer reflector being curved inwardly, the lower portions of the smaller reflector being flared outwardly to meet and to engage the upper sides of said incurved edges, and means for maintaining said portions in engagement with said edges.

22. Reflecting apparatus comprising a

concave reflector, a smaller concave reflector at least in part within the first reflector, portions of the lower edges of the outer reflector being curved inwardly, the lower portions of the smaller reflector being flared outwardly to meet and to engage the upper sides of the said incurved edges, and shoulders on the smaller reflector engaging the lower sides of the outer reflector for maintaining said portions in engagement.

23. Reflecting apparatus comprising a concave reflector, a smaller concave reflector at least in part within the first reflector, portions of the lower edges of the outer reflector being curved inwardly, the lower portions of the smaller reflector being flared outwardly to meet and to engage the upper sides of the said incurved edges, means on the smaller reflector engaging the outer reflector rearwardly of at least a portion of said edges, and ears on the smaller reflector extending outwardly through recesses in the outer reflector forwardly of said edges, the elasticity of the reflector normally maintaining them in engagement in such manner that pressure on said ears will effect a disengagement.

24. Light projection apparatus comprising a reflector consisting of substantially a half sphere and substantially a quarter sphere contained within the half sphere, said quarter sphere having a smaller radius of curvature than the half sphere and the edges of the quarter sphere being flared out to meet the edges of the half sphere, means to secure the two reflectors together at the edges, and means for attaching the reflectors to the lamp ferrule in such manner that the elasticity of the reflectors tends to hold the last mentioned means in position on the ferrule.

25. Light projection apparatus comprising a reflector consisting of substantially a half sphere and substantially a quarter sphere contained within the half sphere, said quarter sphere having a smaller radius of curvature than the half sphere and the edges of the quarter sphere being flared out to meet the edges of the half sphere, and means to secure the two parts together at the said edges.

Signed by me at Boston, Massachusetts, this twenty-second day of September, 1916.

ADELBERT AMES, JR.
